Application June 19, 1946, Serial No. 677,656

16 Claims. (Cl. 332—26)

1

This invention relates to an oscillator and particularly to an oscillator having a predetermined and controllable frequency variation with reference to a fixed mid-frequency. In many signaling systems, particularly where frequency modulation is present, it is necessary that an oscillator have a fixed calibrated frequency as the carrier from which frequency modulating deviations are provided. The simplest and most accurate means for calibrating frequency include piezo crystals. Such crystals have sharp resonance characteristics and, by themselves, cannot be frequency modulated over a wide range. The usual range of frequency deviation in a frequency modulated communication system is far greater than can be accommodated by any simple crystal circuit.

In accordance with the invention, two vacuum tube amplifiers have their outputs connected in parallel to form a system output. Between the high side of the output and tube inputs is connected a crystal containing circuit and phase adjusting means. The arrangement is such that, under normal conditions, the phases of the input potentials to the amplifiers are shifted in opposite directions with respect to the corresponding effective total anode current. Push-pull modulation of the amplifiers results in variations in amplification of the amplifiers. Thus, the phase relation between the potential inputs and combined plate currents of the amplifiers is varied in response to modulating potentials. In the absence of modulation, the crystal circuit provides a fixed frequency at which the oscillator system stabilizes itself. Of particular importance is a means for stabilizing the crystal circuit. This stabilization is due to the connection of the crystal in the circuit so that only its series resonant properties are effective, the shunt capacitance of the crystal being neutralized by a parallel resonant circuit containing the crystal. In shunt to the crystal part of the circuit is an inductor of such a value that its inductive reactance at the mid-frequency is numerically equal but opposite in sign to the capacitive reactance of the shunt capacitance of the crystal and distributed capacitance of both inductor and crystal arm of the circuit. Thus, the effect of these capacitances on the oscillations are suppressed making far more stable operation. Thus, desirable operating characteristics for the system above and below crystal resonance is provided.

For a more complete explanation of the invention, reference will now be made to the drawings wherein Figure 1 shows a circuit diagram of one form of the invention, and Figure 2 shows a cir-

2

cuit diagram of a modified form of the invention.

Referring to Figure 1, vacuum tube 10 has cathode 11 connected by wires 12 and 13 to any suitable source of heating current, here shown as battery 14 merely by way of example. Vacuum tube 10 has control grid 16 connected through grid resistor 17 to the cathode. Grid 16 is also connected through condenser 18 to junction 19. Vacuum tube 10 has accelerating electrode 21 connected to junction 22. Junction 22 is connected through blocking condenser 23 to cathode 11 by lead 12. The cathode is also connected to center tap 24 of any source of modulating potential, here shown as transformer secondary 26. Secondary 26 has one end terminal 27 connected to suppressor electrode 28 of vacuum tube 10. Anode 30 of vacuum tube 10 is connected by a suitable lead to junction 31.

A second vacuum tube 35 has cathode 36 connected to wires 12 and 13. While the cathodes of both tubes are shown as of the directly heated cathode type, it is understood that indirectly heated cathodes may be used. Vacuum tube 35 has control grid 37 connected through grid resistor 38 to the cathode, this same grid also being connected through inductor 39 to junction 19. Vacuum tube 35 has accelerating electrode 40 connected to junction 22. Suppressor electrode 42 is connected to outer terminal 43 of transformer winding 26. Vacuum tube 35 has anode 45 connected by a suitable lead to junction 31. Junction 31 is connected to junction 46 of phase inverting circuit 47 comprising inductor 48, condenser 49, inductor 50 and condenser 51, all connected in series with each other to form a generally parallel resonant circuit. Junction 52 between inductor 48 and condenser 49 is connected by wire 53 to the positive terminal of a suitable source of potential shown, for example, as battery 55. The negative terminal of this source of potential is connected by wire 56 to the cathode circuit. Wire 53 is also connected through dropping resistor 57 to grids 21 and 40 of the two vacuum tubes.

Inductors 48 and 50 together with the coupling capacitor 49 and tuning capacitor 51 form a phase reversing network which may be tuned to resonance by movable core 60 of metal, such as iron for example.

Between inductor 50 and condenser 51 is junction 61. Between junction 61 and junction 19 is connected a piezo crystal circuit consisting of crystal 62, including suitable mounting means, all shunted by inductor 63. The output of the entire system is taken from junction 31 through blocking condenser 64 and cathodes while modu-

lating input for the system may be provided by means of transformer primary 65 cooperating with secondary 26. Such modulating potentials may be at any suitable frequency. Thus, if audio frequencies are used, transformer 66 including primary 65 and secondary 26 may be of the iron core type. On the other hand, if frequencies are too high for the use of iron cores, then air core transformers or capacitance coupling may be used.

Referring to the crystal circuit, inductor 63 has such a value that at the operating frequency its reactance substantially balances not only the reactance due to the shunt capacitance of crystal 62 but also that due to the distributed capacitance of the crystal containing branch of the circuit as well as the distributed capacitance of inductor 63 itself. Thus, at the desired operating frequency in the absence of modulation, this shunt circuit presents a high impedance between junctions 19 and 61 so that only the series reactance elements of the crystal are effective. The circuit between junctions 46 and 61 forms a phase reversing network which may be tuned to resonance by controlling the coupling between inductors 48 and 50, such as by moving core 60. It is, of course, possible to effect this tuning by varying either or both of condensers 49 and 51.

Capacitor 18 and inductor 39 are so proportioned with respect to resistors 17 and 38 that, at the operating frequency of the system, substantial phase shifting will occur. Thus, with respect to the potential at junction 19, the potential at grid 37 will be retarded in phase, while the potential at grid 16 will be advanced in phase. Therefore, a corresponding phase shift of the plate currents in tubes 35 and 10 will occur. Consequently, the potential of junction 31 with respect to line 12 will be determined by the vector sum of the plate currents in the two vacuum tubes.

The potential at junction 61 is 180 degrees out of phase with respect to the potential at junction 31. The phase relations necessary for oscillation are therefore provided.

Resistors 17 and 38 may be the usual grid resistors having a value of 100,000 ohms or more. The value of resistor 57 will depend upon the potential in line 53 due to B supply 55 and the bias potential to be maintained upon accelerating electrodes 21 and 40. Condenser 23 is provided for blocking purposes and otherwise should readily by-pass all frequencies.

It is evident that vacuum tube 10, in the absence of modulation, tends to behave like a capacitive reactance, while vacuum tube 35 tends to simulate an inductive reactance.

Assume now that suppressor electrode 28 of vacuum tube 10 has its potential increased positively with respect to cathode 11. The amplification of tube 10 will, therefore, be increased and result in increased plate current. Conversely, the potential of suppressor electrode 42 of amplifier 35 will be decreased and the amplification of this tube will be decreased. With no modulating potentials, the tubes may be adjusted to have equal amplification and equal plate currents although these plate currents are displaced in phase with respect to each other. With push-pull modulating potentials on electrodes 28 and 42, the vector sum of the two plate currents will be displaced in phase as compared to the vector sum of the plate currents without modulating potentials. The absolute magnitude of the vector sum will remain generally constant with various phase changes.

In order to maintain the entire system in oscil-

lation, it is necessary that the sum of all phase shifts around a complete oscillating circuit including vacuum tubes be an integral number of 360 electrical degrees. Since the effective phase 5 shifts through vacuum tubes 10 and 35 are varied by modulation, it follows that the frequency of the entire circuit will shift accordingly. Thus, in the example previously given where electrode 28 has its potential raised above cathode 11 and 10 electrode 42 has its potential dropped toward cathode 36, the resulting effect on the entire system will be to raise the oscillating frequency. The reverse will happen if the potential of electrode 42 goes up and the potential of electrode 28 15 goes down. It will be understood that the frequency of oscillation of the entire system will be high in comparison to the frequency of modulation at electrodes 28 and 42 respectively.

Inasmuch as the network between junctions 46 20 and 61 is used to produce a phase shift of 180 degrees or any odd number of such shifts, it follows that other phase reversing means such as vacuum tubes may be utilized. It is also clear that the amplification of tubes 10 and 35 may be 25 varied in other manners. Thus, injection of the modulating potentials at cathode or anode or the grid nearest to the cathode are all well known and may be utilized. It is also possible to apply the modulating potentials to any two electrodes, such 30 as anode and grid, instead of the usual cathode and other electrode arrangement. The output of the system may be alternatively taken from junction 61 or junction 19 or coupled to inductors 48 or 50, or other well known manner and may be 35 fed to frequency multipliers for operation in suitable frequency bands.

Referring now to Figure 2, a modified arrangement is shown wherein vacuum tube 70 has cathode 71 connected to lead 72. Tube 70 has anode 40 73 connected to junction 74 in line 75. Line 75 is connected through blocking condenser 76 to junction 77. Junction 77 has crystal 78 and crystal containing circuit including crystal holder connected between it and junction 79. Inductor 45 80 is shunted around the crystal by connecting the same to junction 77 and 19. It is understood that inductor 80 substantially neutralizes the shunt capacitance of crystal 78, the distributed capacitance of the crystal containing branch of 50 the circuit and the distributed capacitance of inductor 80 at the frequency of oscillation. Junction 79 is connected through inductor 82 to junction 83. Junction 83 is connected by lead 84 to control grid 85 of vacuum tube 70. Vacuum tube 55 70 has accelerating electrode 86 connected to junction 87 and thence through resistor 88 to a suitable source of B plus potential.

Vacuum tube 90 has cathode 91 connected to lead 72, this lead being connected to the negative 60 terminal of the B supply. Tube 90 has control grid 92 connected by wire 93 through inductor 94 to junction 83. Wire 93 is connected to wire 72 through grid resistor 96.

Vacuum tube 90 has accelerating electrode 97 65 connected to junction 87. Between junction 87 and line 72 is by-pass condenser 98. Vacuum tube 90 has anode 99 connected to junction 100 on lead 75. From junction 100, an output circuit through blocking condenser 101 is provided.

Between junction 100 and B plus is choke 102. Vacuum tubes 70 and 90 have suppressor electrodes 103 and 104 respectively connected to the outer terminals of transformer secondary 105. Winding 105 has center tap 106 connected to the 75 cathode circuit. Secondary 105 has associated

therewith primary 107 for providing modulating potentials. The inductance of the inductor 82 may be adjusted by iron core 110. The inductance of inductor 94 may similarly be adjusted by an iron core.

Shown in dotted lines are capacitances 111 and 112 between the cathodes of the tubes and the opposite sides of inductor 94. In practice, the input capacitance of control grids 85 and 92 to ground will usually suffice and function as capacitors at the places indicated.

Inductor 82 is designed so that the phase shift between crystal 18 and control grid 85 is less than 180 degrees. Inductor 94 on the other hand should provide a phase shift across it which is twice the difference between the previous phase shift and 180 degrees. Thus, as an example, if inductor 82 provides a phase shift of 120 degrees, then the phase shift provided by inductor 94 should be two times 180 degrees minus 120 degrees or 120 degrees.

It will be seen, therefore, that the invention provides two vacuum tube amplifiers having their output circuits connected in parallel relation to form an output for the entire system. Between the output and inputs of the two amplifiers, there is disposed suitable phase inverters and piezo-crystal circuits for insuring a feedback of output energy to the tube inputs to maintain oscillation. By having the potentials at the inputs of the two tubes displaced in phase with respect to their respective anode potential, the amplifiers simulate reactances, the two having opposite signs. Push-pull modulation of the tube amplifiers results in effectively varying the magnitude of the simulated reactances. The crystal control circuit itself has suitable neutralization of shunt and distributed capacitances as to provide a crystal circuit of sharp resonance with generally symmetrical reactance properties on opposite sides of its series resonance frequency. Thus a system is provided which will oscillate at high stability at crystal frequency or at a controlled deviation therefrom. The relationship between modulating potential and deviation frequency is dependent upon circuit constants and, in general, can be made proportional whether the frequency deviation is above or below the crystal frequency.

What is claimed is:

1. An oscillating system comprising two vacuum tube amplifiers each having input and output circuits respectively, connections disposing said output circuits in parallel to form an output for the system, phase shifting means having output connections to said tube input circuits, a piezo crystal and phase reversing means, comprising a tuned circuit, in series between the input of said phase shifting means and the combined output of said tubes, said phase reversing means and phase shifting means providing a phase advance between the input potential and output current for one tube and a phase retardation between the input potential and output current for the other tube, and means for modulating said tubes in push-pull so that the amplification of said tubes are oppositely affected.

2. An oscillating system comprising two vacuum tube amplifiers each having input and output circuits respectively, connections disposing said output circuits in parallel to form an output for the system, phase shifting means having input and output connections, means connecting the outputs of said phase shifter to said tube input circuits, a piezo crystal circuit and phase reversing means in series between the input of said

phase shifter and the combined output of said tubes, said phase reversing means and phase shifting means providing a phase advance between the input potential and output current for one tube and a phase retardation between the input potential and output current for the other tube, reactance means for neutralizing the shunt capacitance of the crystal, and means for modulating said tubes in push-pull so that the amplification of one tube is oppositely affected to that of the other tube.

3. An oscillating system comprising two vacuum tube amplifiers each having cathode, control grid and anode electrodes, means for connecting said two anodes together to form an output terminal for the system, means for connecting said cathodes together to form the other output terminal, a phase shifter having an input terminal and two output terminals, means for connecting a phase shifter output terminal to a control grid respectively, a piezo crystal containing circuit connected in series between the phase shifter input terminal and the system output terminal, means for tuning said inverter circuit to said crystal resonance frequency, an inductor connected across said crystal for neutralizing the shunt capacitance of said crystal and the distributed capacitance of said inductor, a source of modulating potential, and means for applying said modulating potential in push-pull relation to said two amplifiers to control their respective amplifications.

4. The system of claim 3 wherein each vacuum tube amplifier has an additional control electrode and wherein said modulating potentials are impressed upon said additional control electrodes.

5. An oscillating system comprising two vacuum tube amplifiers each having cathode, control grid and anode electrodes, means for connecting said cathodes and anodes together to form output terminals for the system, grid resistors between said control grids and cathodes, a phase shifter having an input terminal and two output terminals, said phase shifter having a condenser in one branch and an inductor in the other branch, means for connecting the outputs of said phase shifter to said control grids respectively, a piezo crystal containing circuit connected between said phase shifter input and a junction point, a resonant phase inverter circuit connected between said junction and the common anode output terminal, said resonant circuit being tunable over a range broad in comparison to the resonant frequency band of said crystal circuit, an inductor connected across the crystal, said inductor having such a value as to neutralize for the desired operating frequency the shunt capacitance of the crystal plus the distributed capacitance of the crystal circuit plus the distributed capacitance of the inductor, a source of modulating potential and means for applying said potential to said two amplifiers in push-pull to affect the amplification of said amplifiers.

6. The system of claim 5 wherein said resonant circuit includes a pair of inductors and wherein the tuning means comprise means for varying the value of said inductors and the coupling therebetween.

7. An oscillating system comprising two vacuum tube amplifiers each having cathode, control grid, additional control grid and anode electrodes, means for connecting the cathodes and

anodes respectively to provide common anode and cathode output terminals for the entire system, resistance means connected between the cathodes and grids, a condenser and an inductor connected in series between said two control grids and forming a phase shifter, a piezo crystal containing circuit and phase inverter connected between the junction of said condenser and inductor on the one hand and the junction of said two anodes on the other hand, said crystal containing circuit having an inductor for neutralizing the shunt capacitance of said crystal as well as the distributed capacitance of the crystal containing circuit, a source of modulating potential and means for applying said potential to said two additional control electrodes to vary the amplification of said tubes in an opposing sense.

8. An oscillating system comprising two vacuum tube amplifiers each having cathode, control grid and anode electrodes, means for connecting the cathodes and anodes respectively together to provide output terminals for the entire system, a crystal containing circuit and one inductor in series between the two anodes and control grid of one tube, a second inductor between the two control grids of both tubes, means for coupling said two inductors together, and means for applying modulating potentials to said tubes to vary the amplification thereof in opposing senses, said two inductors cooperating with input tube capacitances to provide phase shifting of potentials impressed upon said two control grids, the potentials of said two grids having respective phase advance and lag with reference to the respective combined anode currents and an additional inductor is shunted around said crystal, said inductor neutralizing the shunt and distributed capacitance of the crystal containing portion of the circuit.

9. An oscillating system comprising two vacuum tubes each having cathodes, control grids and anodes respectively, means for connecting said cathodes together to form one output terminal for the system, means for connecting said anodes together to form another output terminal for the system, a blocking condenser, crystal containing circuit and inductor connected in series between the other output terminal of the system and one control grid, an additional inductor between said one control grid and the other control grid, resistance means connecting said con-

trol grids and cathode, said one inductor providing a phase shift less than 180 degrees between the crystal and one control grid, said other inductor providing a phase shift substantially equal to two times the difference between 180 degrees and the first-mentioned phase shift, and means for modulating said tubes to vary the amplification thereof in opposing senses.

10. The system of claim 9 wherein an inductive reactance is connected across the crystal containing circuit to neutralize the shunt and distributed capacitance of the crystal and crystal containing circuit.

11. The system of claim 9 wherein said two inductors have coupling therebetween and wherein means are provided for varying said coupling.

12. The system of claim 9 wherein mutual coupling between the two inductors are provided and wherein an inductor in shunt to the crystal is provided to neutralize the equivalent shunt capacitance of the crystal.

13. The system of claim 9 wherein each of said vacuum tubes has an additional control electrode and wherein said modulating potentials are impressed on said two additional control electrodes, the modulating difference in potential existing between said two additional control electrodes.

14. The system of claim 9 wherein an additional condenser is connected between cathode and control grid of each tube.

15. The system of claim 9 wherein an additional condenser is connected between cathode and control grid of each tube, and wherein an inductor in shunt to the crystal is provided to neutralize the equivalent shunt capacitance of the crystal.

16. An arrangement according to claim 1, further comprising means coupled in shunt with said crystal and tuned therewith whereby only the series reactance elements of the crystal are effective in the associated circuits.
